UNITED STATES PATENT OFFICE.

FREDERICK WM. GEORGE, OF ROCKAWAY BEACH, NEW YORK.

COOLING APPARATUS FOR INTERNAL-COMBUSTION ENGINES.

1,145,137.

Specification of Letters Patent.

Patented July 6, 1915.

Application filed November 24, 1914. Serial No. 873,805.

To all whom it may concern:

Be it known that I, FREDERICK WM. GEORGE, a citizen of the United States of America, residing at Rockaway Beach, in the county of Queens and State of New York, have invented new and useful Improvements in Cooling Apparatus for Internal-Combustion Engines, of which the following is a specification.

This invention relates to improvements in apparatus for cooling internal combustion engines and has particular application to apparatus of the type in which air or gas is passed through the liquid of the circulatory cooling system.

In carrying out the present invention, it is my purpose to provide apparatus for cooling internal combustion engines wherein the circulating water flowing from the engine back to the radiator will be divided up into individual streams and subjected to a blast of air so that the cooling medium bearing the heat units will be rapidly and effectively cooled and then passed through the radiator for further cooling so that when this portion of the cooling medium again flows through the water jackets of the engine cylinders and other parts, such cooling fluid will be in a condition to receive the heat units from the cylinders and carry the same away so that they may be dissipated by the air blast and radiated from the cooling cells of the radiator.

It is also my purpose to provide apparatus of the class described which may be installed and maintained at a minimum expense and wherein the cooling liquid of the engine will be effectively and rapidly relieved of the heat units therein.

With the above and other objects in view, the invention consists in the construction, combination and arrangement of parts hereinafter set forth in and falling within the scope of the claims.

In the accompanying drawings, Figure 1 is a view in side elevation of an internal combustion engine provided with cooling apparatus constructed in accordance with the present invention. Fig. 2 is a fragmentary vertical sectional view through the radiator showing the means for dividing the water into individual streams and blowing air thereon. Fig. 3 is an enlarged fragmentary cross sectional view through the radiator taken at right angles to Fig. 2. Fig. 4 is a horizontal sectional view through

the radiator showing the cooling tube in top plan. Fig. 5 is a perspective view of the cooling tube removed from the radiator. Fig. 6 is a vertical central sectional view through the radiator showing a modified form of the invention. Fig. 7 is a similar view taken at right angles to Fig. 6.

Referring now to the drawings in detail, 1 designates a radiator of any approved construction having the upper end portion thereof formed to provide a compartment 2 disposed above the cooling cells and provided with a top edge wall 3 formed centrally with an upstanding vent spout 4. 60 Leading from the lower end edge of the radiator 1 and in open communication with the cooling cells thereof is a pipe 5 extending to and connected with the water jackets of the engine cylinders, and connected with the upper ends of the water jackets is a pipe 6 leading into the upper end of the radiator 1 through one of the walls of the chamber 2. 65 By means of this construction, it will be seen that the cooling water may circulate 70 through the cooling cells of the radiator and the water jackets of the engine cylinders, such water flowing from the bottom of the radiator through the pipe 5 into the cooling jackets of the engine cylinders, and then 75 through the pipe 6 back to the upper end of the radiator.

In accordance with my present invention, a tube 7 is disposed within the compartment 2 and extends longitudinally of the radiator 90 and has the opposite ends thereof secured by means of appropriate brackets 8 to the respective end walls of the radiator so that the tube may be supported within the chamber 2 in parallelism with the top edge wall 95 thereof. The top wall of the tube 7 is formed with one or more longitudinally extending rows of orifices 9 and secured to the top portion of the tube and extending longitudinally thereof and inclosing the 100 orifices 9 is an inverted trough 10 semi-circular in cross section and having the top portion thereof provided, approximately centrally, with an upstanding nipple 11 connected with the adjacent end of the pipe 6. 105 One end of the tube 1 opens into the cells of the radiator and the opposite end portion thereof is formed with a right angular elbow 12 within which is disposed a blast fan 13 driven from the engine through the 110 medium of suitable driving means 14.

In practice, as the water circulates through

the cooling system, such water passes into the trough 10 through the pipe 6 and flows over the top portion of the tube 1 dropping through the orifices 9 in such portion of the tube into the tube. As these individual streams of water flow into the tube an air blast from the fan 15 strikes the same, thereby effectively cooling water preparatory to the latter passing through the cells of the 10 radiator, and as the water passes through the cells of the radiator the action of the air blast is augmented and the water further cooled. This air from the blast fan 13 is preferably blown down through the cells 15 1 and tapped into the lower end of the radiator is the lower end of a vertical exhaust pipe 15, such pipe having the upper end thereof terminating above the water line of the radiator so that the air may be 20 exhausted from the system.

In the modified form of the invention illustrated in Figs. 6 and 7, the lower half of the tube 1 is removed or cut away and suspended from the under surface of the 25 remaining portion of the tube contiguous to the respective rows of orifices 9 are cloths 16 depending into the radiator and designed to receive the water passing through the orifices 9 and hold such water in contact 30 with the air for a relatively long time.

In practice, I wish it to be understood that the lower portion of the radiator, that is, the portion below the chamber 2, may be in the form of a tank in lieu of cooling 35 cells of coils.

From the foregoing description taken in connection with the accompanying drawings, it will be seen that I have provided a cooling system for internal combustion engines 40 whereby the cooling liquid after passing through the engine cylinders is divided into a plurality of independent streams and subjected to an air blast, thereby enabling the fluid to be rapidly and effectively cooled.

While I have herein shown and described certain preferred forms of my invention by way of illustration, I wish it to be understood that I do not limit or confine myself to the precise details of construction herein 50 described and delineated, as modification and variation may be made within the scope of the claims without departing from the spirit of the invention.

The front wall of the chamber 2 is preferably formed with a rectangular opening 2' and hinged to the upper wall of the opening 2' is a cover plate 3' normally overlying the opening 2' and closing the latter and capable

of swinging movement out of the opening 2' so that air may enter the chamber 2 through 60 the opening 2' and strike the streams of water and so augment the cooling action of the fan or blower.

I claim:

1. A radiator for the cooling systems of 65 internal combustion engines having a water inlet connection at the upper end thereof and a water outlet connection at the bottom end thereof, a tube disposed within the upper end portion of said radiator and having 70 the wall thereof formed with a series of apertures extending longitudinally thereof, an inverted trough secured to said tube and inclosing said apertures and extending longitudinally of the tube and connected with 75 the water inlet connection of the radiator whereby the water will flow through the trough and through the apertures into the tube in the form of individual jets, and a blast fan at one end of said tube adapted to 80 blow air into the latter against the streams of water therein to facilitate the cooling of such water.

2. A radiator for the cooling systems of 85 internal combustion engines having a water inlet connection at the upper end thereof and a water outlet connection at the bottom end thereof, a tube disposed within the upper end portion of said radiator and having 90 the wall thereof formed with a series of apertures extending longitudinally thereof, an inverted trough secured to said tube and inclosing said apertures and extending longitudinally of the tube and connected with 95 the water inlet connection of the radiator whereby the water will flow through the trough and through the apertures into the tube in the form of individual jets, and a blast fan at one end of said tube adapted to 100 blow air into the latter against the streams of water therein to facilitate the cooling of such water, the portion of said tube opposite 105 from the apertures being cut away and cloths secured to the remaining portion of said tube adjacent to the respective rows of apertures therein and depending therefrom to receive the water and hold the latter in contact with the air for a relatively long time.

In testimony whereof I affix my signature 110 in presence of two witnesses.

FREDERICK WM. GEORGE
